United States Patent Office

Des. 184,159
Patented Dec. 23, 1958

184,159

HOOD, HEADLAMP, AND GRILL UNIT FOR TRACTORS OR THE LIKE

Charles L. Whiting and Delmar D. Berckhan, Waverly,
Iowa, assignors to Schield Bantam Company, Waverly,
Iowa, a corporation of Iowa

Application January 13, 1958, Serial No. 49,212

Term of patent 7 years

(Cl. D14—3)

FIG. 3

FIG. 2

Fig. 1 is a view in perspective from the front of the hood, headlamp and grill unit for tractors or the like showing our new design;

Fig. 2 is a top plan view; and

Fig. 3 is a rear view.

The side opposite that disclosed is substantially the same in appearance as the side shown.

We claim:

The ornamental design for a hood, headlamp, and grill unit for tractors or the like, as shown and described.
